4 Claims. (Cl. 159—47)

This invention relates to a method for concentrating a solution and separating crystals therefrom. In its more specific aspect, this invention relates to a method for concentrating a solution having two or more chemical solutes, crystallizing at least one solute, and separating the crystals from the remaining concentrated solution. The invention is described hereinbelow in detail with reference to electrolytic caustic soda, but it should be understood that the invention is equally applicable to other solutions having chemically different constituents.

In the manufacture of electrolytic caustic soda, the brine charge is partly converted through electrolysis into caustic soda. The liquor withdrawn from the electrolytic cells typically comprises about 8 to 11% sodium hydroxide, 13 to 17% sodium chloride, and the balance water. In commercial practice, the caustic soda is separated from the salt by concentrating the cell liquor in a multiple effect evaporator system to crystallize most of the salt, which is then separated from the mother liquor.

This invention has as its purpose to provide a pre-concentrator for use in treating the feed liquor in combination with the multiple-effect evaporator, whereby substantial economy is realized both with respect to operating costs and capital costs. Reference is now made herein to the specific description and to the accompanying drawings, in which the figure is a diagrammatic representation of the present invention for carrying out our improved process.

In referring to the drawing, there is now described the concentrating of a solution comprising caustic soda and salt as obtained from diaphragm electrolytic cells. The liquor passes from the electrolytic cell (not shown) through a suitable supply line 10. The cell liquor is then pumped through the tubes of a plurality of regenerative heaters 12, 14, 16 and 18. The regenerative heaters are heated by indirect heat exchange, and the temperature of the cell liquor is increased gradually as it passes from one heater to the next. Regenerative heaters 12, 14 and 16 are heated by indirect heat exchange by the vapors flashed in the several flash coolers 44, 42 and 40 respectively, and condensed vapors from the heat exchanger 91 of the first effect 58 of the multiple effect evaporator system are recycled by line 99 to heat regenerative heater 18 by liquid to liquid indirect heat exchange, as described hereinbelow in greater detail. Thus, the cell liquor flows from line 10 to heater 12, and then through line 13 to heater 14, then via line 15 to heater 16, and then through line 17 to heater 18. The pressure in the regenerative heaters is sufficient to suppress boiling of the liquor and also is sufficient to transport the cell liquor through the regenerative heaters to the pre-concentrator. The number of regenerative heaters employed in the operation can vary, depending upon a number of factors, such as size and the operating temperature range, but the number of heaters should be sufficient to optimize heating with respect to the subsequent flash cooling stages. However, it is preferable to employ a plurality of regenerative heaters in that, in bringing the liquor to the desired elevated temperature, a lesser amount of outside heat supply would be required.

From regenerative heater 18, the cell liquor, which is now at an elevated temperature, is passed via line 20 to preheater 22. Steam is supplied to the preheater 22 from a suitable boiler (not shown) via line 24 and branch line 26, to heat the liquor to a high temperature for admission

2

to the pre-concentrator. The steam condensate from preheater 22 is fed by line 29 to line 36 which returns it to the boiler. When desired, this separate preheater, heated by a steam source, may be omitted.

After the feed liquor has been brought to the desired elevated temperature, and while maintained under sufficient pressure to suppress boiling, the liquor is passed from preheater 22 via line 28 to the pre-concentrator, indicated generally at 30. The pre-concentrator is desirably a falling film type evaporator comprising a vertical shell and tube heat exchanger 32 with tubes communicating with a vapor body 33 disposed below the heat exchanger. Steam is supplied to the shell side of the heat exchanger via line 24 and branch line 31. Because the liquor is maintained at a high temperature and under pressure, the liquor shoots rapidly through the vertical tubes and a substantial amount of liquid is evaporated in the pre-concentrator. The vapors generated are passed from the vapor body 33 through a vapor outlet conduit 34 for use as heating medium in the multiple effect evaporator, described hereinbelow, and the condensate from the preheater 22 and preconcentrator 30 is returned to the boiler by means of a return line 36.

The hot liquor, which now is relatively more concentrated because of evaporation in the pre-concentrator, is then passed through line 38 to a plurality of flash coolers 40, 42, and 44 where flash vaporization occurs. The temperature of the liquor and the operating pressure are reduced in the flash coolers, each successive flash cooler being at a lower temperature and pressure than the preceding one. The liquor enters the first flash cooler 40, which is operated at a lower pressure as compared to the pre-concentrator and the solution adiabatically cools to the boiling temperature corresponding to the pressure existing in the vessel. The vapor generated is passed through branch steam line 46 to regenerative heater 16, thereby heating unit 16 by indirect heat exchange. The concentrated liquor is then passed through line 41 to flash cooler 42, maintained at a lower pressure than flash cooler 40, where further evaporation occurs, and similarly, vapor generated is passed via line 48 to regenerative heater 14 to heat that unit by indirect heat exchange. Still further evaporation of the liquor occurs in flash cooler 44, maintained at a still lower pressure, to which the liquor is fed by line 43 and the steam generated is conducted through line 50 to heat regenerative heater 12 by indirect heat exchange. As the liquor is directed through the series of flash coolers, the resultant cooling and vaporization of some of the solvent will supersaturate the solution with respect to the sodium chloride, and sodium chloride crystals are produced which serve as nuclei or seeds to effect growth in the multiple effect evaporators. This stage of the process is particularly important in that controlled nucleation or seed generation affects the size and habit of the crystals developed in the multiple effect evaporators, which is important in order to achieve optimum crystals and to improve the plant efficiency as affected by the separation of the crystallized solute from the mother liquor. It will be understood that the system of regenerative heaters and flash coolers shown in the drawing is purely illustrative of how savings in capital and operating costs can be realized, and the number, use, and arrangement of such units will depend upon the conditions encountered for each particular installation, such as steam pressure available, the degree of concentration of the feed liquor, the degree of concentration desired to control nucleation, and the like.

The mother liquor from the last flash cooler 44 flows from line 52 to the multiple-effect evaporator system, and, as illustrated, the effects are operated at successively lower temperatures. As illustrated in the drawing, there is the second-effect evaporator 54, the third-effect evaporator 56, and the first-effect evaporator 58, all of conventional

forced circulation design, and the mother liquor is conducted via line 52 to the second effect of a three-effect evaporator system, but it should be understood that the mother liquor may pass first to any of the three evaporators. The numbering employed in referring to the particular effect in the system is in order of decreasing operating pressure. The feed liquor, which contains sodium chloride crystal nuclei, is fed to the second effect of the multi-effect evaporator system which is operated at a sub-atmospheric pressure. A recirculation system is provided for each evaporator-crystallizer effect. The recirculation system for the second effect 54 comprises slurry outlet line 60, a recirculation pump 62, line 61 from the pump to heat exchanger 63 and a return slurry inlet line 64 which results in admixture of slurry with feed liquor from line 52. The recirculation system for the first effect 58 comprises slurry outlet line 90, a slurry recirculation pump 92 which feeds slurry by line 94 to heat exchanger 91 from which line 96 feeds it to first effect 58. The recirculation system for the third effect 56 comprises outlet line 130 which feeds slurry to pump 131 which by line 132 feeds the slurry to heat exchanger 133 from which line 134 feeds the slurry to the third effect 56.

Under the operating conditions employed, supersaturation of the solution with respect to the salt, hence further crystal growth, is produced by the combined cooling and evaporation of the feed liquor. The seed crystals are grown to a size and quality that facilitates their efficient separation from the mother liquor. Vapors generated upon the evaporation of the water from the liquor are withdrawn from the vapor zone of the crystallizer through line 68 and delivered to the next effect 56 in the multiple-stage system as the heating medium for that effect by conventional heat exchange. Crystal outlet means 66 is located near the bottom of the crystallizer vessel 54 for removal of the crystal slurry suspended in mother liquor.

Magma comprising a slurry of product crystals of desired size suspended in mother liquor is discharged from the crystallization section of the evaporator-crystallizer 54 and transferred to slurry tank 70 through line 71. The slurry tank 70 is desirably provided with a conical bottom or trun-conical bottom, and the salt crystals settle into the conical bottom portion and are removed via line 72. The liquor is now relatively more concentrated, and the mother liquor, having an increased content of caustic soda as compared to the original feed liquor from the electrolytic cell, but still containing a substantial percentage of sodium chloride, is decanted or withdrawn from the slurry tank as by a suitable pump means (not shown) through line 76 to the third-effect evaporator 56 of the multiple-stage evaporator system maintained under subatmospheric pressure. Here again, the liquor is concentrated by evaporation and, under the operating conditions, an amount of salt crystallizes out of solution and the slurry is withdrawn through outlet means 78. The vapors generated pass from the vapor zone of the crystallizer via line 80 to barometric condenser 82 which maintains a vacuum in this third effect. Similar recirculation means described above with respect to evaporator effect 54 are provided for the third effect 56. Thus, mother liquor is removed by line 130 and pump 131 and sent through line 132, through heat exchanger 133 and by line 134 to third effect 56. Hot condensate from heat exchanger 63 is fed by line 106 to heat exchanger 133. Condensate from heat exchanger 133 is sent by line 135 to storage. The magma containing crystals of desired size is passed to a second slurry tank 84 through line 78. Salt crystals which settle in the lower conical portion of the slurry tank are withdrawn through line 88 to the first slurry tank 70. In this manner, the salt crystals from slurry tank 84 are washed by the slurry in tank 70, thereby removing some of the sodium hydroxide in the salt.

The relatively clear mother liquor, containing a still higher percentage of caustic soda, is withdrawn from tank 84 via line 88 to the first effect 58 of the multiple-stage evaporator system maintained at about atmospheric pres-

sure. The liquor is withdrawn from evaporator effect 58 via line 90 and is recirculated through suitable recirculating means, including pump 92 and line 94 where it admixes with feed from line 88, and is fed through heat exchanger 91 and introduced to the evaporator through line 96. Vapors generated in pre-concentrator 30 are transported from the vapor body 33 by line 34 to the heat exchanger 91 for use as the heating medium for effect 58 by indirect heat exchange. The vapor condensate from heat exchanger 91 is fed by line 99 to heater 18 from which it is withdrawn by line 140 and fed to heater 16 from which it is fed by line 141 to heater 14 and from it by line 142 to heater 12. Line 143 takes the condensate from heater 12 and carries it to storage. Evaporation occurs in first effect 58 thereby resulting in additional concentration and crystal growth. The vapors generated are withdrawn from the vapor space of the first effect evaporator 58 through line 98 and pass to the heat exchanger 63 associated with the second effect 54 to supply heat for that evaporator. Vapor condensate from heat exchanger 63 is passed through line 106 to heat exchanger 133.

The solution withdrawn from the first-effect evaporator 58 is relatively concentrated with respect to caustic soda and now contains a very low percentage of sodium chloride. This concentrated solution is withdrawn through branch line 102, leading from line 96, to a flash evaporator 103 which may have the same general construction as the evaporator effects in the multiple-stage evaporator system. The flash evaporator 103 is operated under sub-atmospheric conditions and at a temperature lower than the temperature in the first effect 58 whereby flash vaporization occurs. The vapors generated are passed via line 104 directly to the barometric condenser 82 and the condensate reprocessed. The liquor in flash evaporator 103 is recirculated through line 110 at the bottom of the vessel by pump means 112 and return line 114. The substantially crystal-free liquor, circulating in the recirculating means, is withdrawn through branch line 116 to slurry tank 118. Salt crystals in the liquor settle out under gravity and are withdrawn from the conical bottom portion via line 120. The salt withdrawn from slurry tank 118 is washed by the salt and mother liquor in slurry tank 84, thereby effecting progressive washings of the crystal sludge in each of the slurry tanks. The salt crystals withdrawn from the bottom tank in this successive arrangement is passed to a suitable centrifuge 122 for further separation of the salt from the mother liquor, whereby the salt may be recovered and returned to the electrolytic cell for further processing in the manufacture of caustic soda. The relatively clear mother liquor, containing a very low percentage of sodium chloride, is withdrawn from the slurry tank 118 through line 124. The liquor discharge line may pass to a surge tank 126 and then to suitable caustic coolers 128 for further purification and recovery of the caustic soda product.

In the operation of the pre-concentrating and evaporating system in concentrating electrolytic caustic soda cell liquor comprising, for example, about 8.5% caustic soda, 16.5% sodium chloride, and the balance water, the feed liquor from the electrolytic cell, which typically has a temperature of about 140 to 150° F., is fed from line 10 to the regenerative heaters. In these heaters, the incoming cell liquor is heated by indirect heat exchange, by the vapors generated in the flash coolers. In this manner, the feed liquor is heated in regenerative heater 12 to a temperature of about 200° F., and further raised to about 227° F. in heater 14, and further heated in heater 16 to temperature of 257° F. The cell liquor is further elevated in temperature in heater 18 to about 267° F. which was heated by indirect heat exchange by vapor condensate from the first effect evaporator. The cell liquor then flows under pressure to preheater 22 where the liquor is heated to about 329° F. by means of indirect heat exchange with steam from a suitable steam source from lines 24 and 26. The cell liquor, at this elevated temperature and under sufficient pressure to suppress boiling, e.g. 100 p.s.i.g., is

introduced to the pre-concentrator 30 to effect concentration of the solution. The pre-concentrator, for example, of the falling film type, may be maintained at a pressure of about 65 p.s.i.g., and the vapors generated at 312° F. and 65 p.s.i.g. are withdrawn through line 34 to heat exchanger 91 to heat the first effect 58 of the multiple effect evaporator system.

The liquor withdrawn from the pre-concentrator through line 38 is now at a higher concentration, e.g. 13.6% caustic soda, but the concentration and temperature conditions are controlled so that no crystallization occurs until the cell liquor is treated in the flash coolers. In a conventional multiple-stage evaporator system, salt deposits gradually accumulate on the interior walls of the vessels. As a consequence, operations must be discontinued periodically for removing the salt. By reason of our invention, this disadvantage is overcome in that no crystallization occurs in the pre-concentrating stage of the operation. The liquor is cooled in the first flash cooler 40, which is operated at a slightly elevated pressure of about 35 p.s.i.g., and a temperature of about 291° F. The cell liquor is progressively cooled as it passes successively through the flash coolers 42 and 44. Thus, flash cooler 42 may be operated at a temperature of about 261° F. and a pressure of 25 p.s.i.g., and cooler 44 operated at 25 a temperature of about 230° F. and at atmospheric pressure. As explained above, crystallization of sodium chloride occurs in one or more of the flash coolers to generate seed for the multiple-effect evaporators.

The liquor containing some sodium chloride crystals 30 is then passed to the second effect of the multiple-stage evaporator system. This effect 54 is operated under vacuum and at a relatively lower temperature of about 192° F. The composition of the slurry withdrawn through outlet line 71 comprises about 23% caustic soda, 17% sodium 35 chloride, and the balance water. The mother liquor passed to the third effect 56 from slurry tank 70 is evaporated under a vacuum and at a still lower temperature of about 147° F. The slurry withdrawn comprises about 32% sodium hydroxide, 12% sodium chloride, and 56% water. 40 Mother liquor passed to the first effect 58 from slurry tank 84 is treated at an elevated temperature of about 282° F. and atmospheric pressure. The relatively clear mother liquor having a low sodium chloride content is withdrawn from the first effect and passed to the flash 45 evaporator 103 and then to a third slurry tank. Here, the composition of the liquor comprises about 49.5% caustic soda and 2-3% sodium chloride. The slurry is passed to the caustic coolers and cooled to about 80° F. to cause further crystallization of salt, thereby resulting 50 in a solution containing about 1% salt.

In addition to pre-concentrating the feed liquor to facilitate evaporation and separation of the components from the liquor, other attendant advantages of the instant invention include substantial reductions in operating expenditures and capital costs. For example, there is substantial economy in that utilities required are reduced. These include, for example, steam, power, and water, in that the steam generated during the process is utilized for supplying heat at other steps of the operation. The caustic soda feed liquor is processed at a temperature in the pre-concentrator that precludes salting out. The heat transfer surface exposed to salt formation is reduced significantly so that much less interior surface of the equipment requires cleaning. In view of the processing at relatively high pressures, there is a reduction in volume of equipment required, and further, exotic crystallization equipment is obviated. By reason of this invention, it is also possible to expand any existing facility of conventional design in that the invention may be incorporated with the conventional multiple-effect crystallizer design, thereby increasing overall plant production and concomitantly decreasing operating costs.

It should be understood that although the invention was described specifically with reference to the recovery of 75

electrolytic caustic soda, this invention is applicable to recovery from solution of one component from another by crystallizing one solute and separating the crystals from the remaining solution. Other such solutions include, for example, electrolytic caustic potash; chemical caustic soda containing sodium sulfate and sodium carbonate; and brines containing sodium chloride, calcium chloride, and magnesium salts.

What is claimed is:

1. A method for recovering a first solute from liquor and recovering liquor relatively concentrated with respect to a second solute, comprising:

- (a) introducing the feed liquor to a regenerative heater to preheat said feed liquor and maintained under pressure sufficient to prevent boiling;
- (b) introducing the resulting preheated feed liquor to a pre-concentrator vessel and establishing a vapor release zone in said preconcentrator vessel for vaporization of solvent thereby resulting in a relatively more concentrated liquor but having substantially no crystallization of solute;
- (c) passing the liquor from the pre-concentrator to a flash cooler maintained at a lower pressure than said pre-concentrator to effect further vaporization of the liquor and crystallization of solute, and employing the vapors generated in the flash cooler as heating medium for said feed liquor introduced to said regenerative heater;
- (d) passing the liquor, containing crystals, from the flash cooler to a multiple effect evaporator, having heat supplied thereto from the vapor generated in said pre-concentrator by indirect heat exchange, for further vaporization to effect crystallization of solute thereby resulting in a liquor relatively more concentrated than said feed liquor with respect to a second solute; and
- (e) separating a slurry of said crystals produced in said multiple effect evaporator from said concentrated liquor.

2. A method according to claim 1 including a plurality of regenerative heaters being interconnected for series flow, each of said regenerative heaters being operated at successively higher temperatures; and a plurality of flash coolers being interconnected for series flow, each of said flash coolers being operated at successively lower temperatures, whereby the vapors generated in each of said flash coolers are employed as heating medium for said feed liquor introduced to said regenerative heaters in inverse order.

3. In a method for the recovery of chemically different components from liquor wherein hot feed solution is introduced to a multiple effect evaporator whereby evaporation of the solution occurs thereby resulting in a supersaturation of the solution and crystallization, the improvement comprising:

- (a) introducing the feed liquor to a plurality of regenerative heaters being interconnected for series flow, each of said regenerative heaters being operated at successively higher temperatures and maintained under a pressure sufficient to suppress boiling;
- (b) introducing the resulting preheated feed liquor to a pre-concentrator vessel and establishing a vapor release zone in said pre-concentrator vessel for vaporization of solvent thereby resulting in a relatively more concentrated liquor but having substantially no crystallization of solute;
- (c) passing the liquor from the pre-concentrator through a plurality of flash coolers interconnected for series flow, each of said flash coolers being operated at successively lower temperatures and maintained at a lower pressure than said pre-concentrator to effect further vaporization of the liquor and crystallization of solute, and employing the vapors generated in each of said flash coolers as a heating

medium for said feed liquor introduced to said regenerative heaters in inverse order; and
 (d) passing the liquor containing crystals to a multiple effect evaporator to effect vaporization and crystallization of solute and separating the crystal slurry from the resulting liquor. 5

4. In the recovery of chemically different components from liquor by concentrating the liquor in a multiple effect evaporator, the method of treating the feed liquor prior to introduction to said evaporator, comprising:

- (a) introducing the feed liquor to a plurality of regenerative heaters being interconnected for series flow, each of said regenerative heaters being operated at successively higher temperatures and maintained under a pressure sufficient to suppress boiling; 10
- (b) introducing the resulting preheated feed liquor to a pre-concentrator vessel and establishing a vapor release zone in said pre-concentrator vessel for vaporization of solvent thereby resulting in a relatively more concentrated liquor but having substantially no crystallization of solute; and
- (c) passing the liquor from the pre-concentrator through a plurality of flash coolers interconnected for series flow, each of said flash coolers being oper- 15

ated at successively lower temperatures and maintained at a lower pressure than said pre-concentrator to effect further vaporization of the liquor and crystallization of solute, and employing the vapors generated in each of said flash coolers as a heating medium for said feed liquor introduced to said regenerative heaters in inverse order.
